UNITED STATES PATENT OFFICE.

DAVID S. HULFISH, OF TORONTO, ONTARIO, CANADA, ASSIGNOR TO CANADIAN INDEPENDENT TELEPHONE COMPANY, LIMITED, OF TORONTO, CANADA, A CORPORATION OF CANADA.

TELEPHONE SYSTEM.

1,112,140.

Specification of Letters Patent.

Patented Sept. 29, 1914.

Application filed November 26, 1910, Serial No. 594,257. Renewed December 22, 1913. Serial No. 808,274.

To all whom it may concern:

Be it known that I, DAVID S. HULFISH, a citizen of the United States of America, and a resident of Toronto, Province of Ontario, 5 and Dominion of Canada, have invented a new and useful Improvement in Telephone Systems, of which the following is a specification.

My invention pertains to telephone systems and switching devices and has specifically as its object the provision of switching devices suitable for giving service to telephone lines upon each of which is connected more than one telephone station.

15 By my invention I provide a system wherein the operations at the central office are in no way different with a reverting call, namely, when one station upon a multi-party line calls for another station upon the 20 same line, as compared with a call for a station upon any other line of the exchange system.

I accomplish this result by removing the test condition from the answering connective device while applying the test upon the called line with the calling connective device, and by this means permit the calling device to connect with the line because the busy test is not received from the line.

30 Having thus connected with the required line independently of the fact that it may or may not be the line originating the call, I provide means for ringing the required station upon the line by the operation of the 35 switchboard ringing key and without requiring the calling station to hang up the receiver. The operation under the principles of my invention is the same whether the call is reverting or not, although the action of the supervisory signals of a manual

40 switchboard may be such as to enable the operator to distinguish between the two classes of calls, if for any reason such discrimination should be deemed an advantage.

45 This specification is accompanied by four figures of drawings of which Figure 1 shows a complete telephone line, a complete connective device embodying the principles of my invention and the busy test elements of 50 another telephone line; Fig. 2 shows the sub-station equipment of an alternative form of signaling and circuits for multi-party lines; Fig. 3 shows generators and ringing keys adapted to coöperate with the

equipment of Fig. 2; and Fig. 4 shows a 55 modification of Fig. 1.

Referring to Fig. 1, the telephone line composed of conductors 1 and 2 is equipped upon the twisted jack principle. At the sub-station 3, the ringer is connected from 60 conductor 2 to earth. At the sub-station 4, the ringer is connected from the conductor 1 to earth. At the central office, cut-off relay 5, line relay 6 and lamp 7 are connected in a manner understood in the art. The answering jack 8 is associated with the line lamp 7. Calling jacks 3' 3' have their long springs connected to conductor 2 while calling jacks 4' 4' have their long springs connected to conductor 1. The connecting plug 9 pair extends from answering plug 8 to calling plug 10. Talking battery 11 is connected through the split repeating coil 12. The ringing key 13 is provided with six switching springs as is usual with ringing keys 75 and has also two pairs of springs normally closed which, when the ringing key is operated to ring, act to open the circuit of both sides of the talking pair between the plug 9 and the repeating coil 12, thus isolating the 80 conductors of the calling line from the repeating coil bridge. The listening key 14 has one normally closed contact through which the tip of the plug 10 is connected to the repeating coil 12. When the listening 85 key is operated to connect the telephone 15, the telephone is connected to the outer springs 16, 17, of the key, the spring 18 is broken from the spring 16 and makes contact with the spring 19. This connects the 90 tip of the plug 10 while the operator is listening in through the circuit 20, 13, 21, 18, 19, 22 and helix of relay 23 to earth. The telephone 15 has no permanent connection to the tip of testing plug 10 whereby any 95 audible test might be received directly. The ordinary action of testing is as follows, assuming that the test conductor 24 of a desired line is connected to the main battery 11 by reason of the insertion therein of a 100 connecting plug 10': When the tip of the plug 10 touches the test ring 24' of the desired line, current flows from earth through battery 11 plug 10' conductor 24, test ring 24', tip of plug 10, conductor 20, key 13, conductor 21, springs 18, 19, conductor 22 and helix of 23 to earth energizing relay 23. By the operation of the armature of relay 105

23, the body of plug 9 is disconnected from main battery 11 and the conductor 25 is connected to the conductor 22 subsequently. This permits a current from the conductor 22 through the conductor 25, and one corner of coil 12 to earth; this current produces an audible signal in the receiver 15. In the case of a reverting call, the condition is that of plug 10 attempting the test upon a 10 test ring which is busy by reason of its connection with plug 9. This is indicated by the dotted line 26. When the tip of 10 touches the test ring of 3', current flows through 11, 27, 28, 29, 30, 31, 9, 8, 3', 10, 15 20, 13, 21, 18, 19, 22 and helix of 23, energizing 23. The relay 23 has its core charged by current received through its own back contact; it acts therefore as a buzzer in case the contact between plug 10 and jack 3' is maintained as described. Since the mechanical construction of the relay 23 is such that the contact of its element 31 always is broken before the contact of its element 32 is closed, it is impossible for a circuit ever to be closed 20 which will include the battery 11 in series with conductors 30 and 25 since conductor 30 is removed from conductor 22 before conductor 25 is applied to conductor 22 and thus the test-responsive device, namely, the 25 operator's receiver 15, will not be subjected to the "line-busy" signal under the condition of the reverting test.

The operator, receiving no busy indication when testing the jack 3', will insert the plug 35 10 in that jack, and of course, without removing her plug 9 from jack 8. Her next action is to ring. Assuming that station 4 has called for station 3, the action of the ringing key 13 is to apply the earth of 40 spring 33 through conductor 20 and the short spring of jack 3' to conductor 1, and also to apply the generator 35 of the spring 34 to plug 10 through conductor 36, and thence through the long spring of jack 3', 45 to the conductor 2 whence current will flow through the ringer of station 3 to earth and through the telephone bridge of station 4 which is closed by its act of calling and to conductor 1 and to earth through spring 33. 50 While the ringing condition has been existing, the ringing key 13 by its four middle springs has separated conductor 37 from conductor 38 and conductor 39 from conductor 40, thereby preventing a short-circuiting of the line by the low resistance of 55 the repeating coil 12 and preventing a waste of ringing current from the calling plug through the answering plug.

To avoid the objectionable feature of the 60 current flow from the ringing generator through the talking bridge of the calling telephone station, I prefer a signaling circuit as illustrated on Figs. 2 and 3. In this case harmonic or tuned ringers are suitable. 65 At stations 41 and 43, the ringers are con-

nected from wire 2 to earth and at stations 42 and 44 the ringers are connected from wire 1 to earth. The connections of ringing keys, 51, 52, 53, 54 are such as to connect together the two conductors of the called line and to ring from both to earth by means of the proper generator 61, 62, 63, 64, thereby operating the properly tuned one of the four ringers and without passing through the telephone bridge of the line any current other than a very small current due to any unbalanced detail of the line.

In Fig. 2 the conductors 1 and 2 are the conductors numbered similarly in Fig. 1 and in Fig. 3 the terminals 33' 34' are the terminals of the ringing key springs 33 and 34.

In Fig. 4, a modification is shown. Resistances 45, 46, are connected between conductors 37 and 38 and between conductors 39 and 40. These resistances are sufficiently high to enable ringing over the telephone line to be accomplished, and the action of key 13 does not increase the resistance of the answering plug beyond the limit set by the resistance 45 and 46. Without the resistance 45 and 46, the action of the key 13 by its middle springs is to raise the resistance of the conductors of the plug 9 to a very high value by opening all nominally conductive connections.

It is obvious that many modifications not specifically shown may be made without departing from the spirit or scope of my invention. If the resistance between plug 9 and repeating coil 12 be sufficiently high when measured along the paths to earth, then it becomes unnecessary for key 13 to increase that resistance still farther to obtain successful ringing. I have shown a switchboard system of a well-known type modified to embody my invention; switchboard systems of other types obviously may be modified but the requirements would be different in detail.

In the specific application of my invention herein illustrated, the signal lamp 47 will be extinguished as soon as the operator inserts the plug 10 in the jack 3' by reason of the bridge of the calling station 4 across the conductors 1 and 2. This will indicate to the operator that the call is a reverting one. Furthermore, when the ringing key 13 is operated, both of the lamps 47 and 29 will be illuminated since the ringing key breaks the conductors of both plugs and causes the release of both supervisory relays. This will be an additional indication to the operator that the call is a reverting one. The operation of the switchboard for the completion and supervision of the call does not differ by reason of these indications. While the operator is listening upon a completed connection not reverting, current for talking for the called line follows the parallel paths from plug 10 through helix of 23 130

to earth and through one corner of repeating coil 12 in series with the armature and contact of test relay 23.

Relay 48 is energized and connects conductor 30 to plug 9 during the period when plug 10 is inserted in any jack, hence after plug 10 is inserted the energization of relay 23 by the listening of the operator will not remove the test connection from the body of plug 9.

Having thus described my invention, what I claim as new and desire to secure by United States Letters Patent is:

1. In a telephone system, a telephone line; a plurality of central office jacks for said telephone line; a connecting plug-pair comprising in part a calling plug and answering plug and a test relay; a main battery; a circuit from said battery through an armature contact of said relay to the body of said answering plug; a circuit from the tip of said calling plug to and through the helix of said test relay; and an auxiliary test circuit from a contact of said relay, said relay being adapted to act when energized, first, to open the connection between said battery and said answering plug, and second and subsequently to close circuit between said auxiliary test circuit and said calling plug, substantially as described.

2. In a telephone system, answering and calling plugs; answering and calling jacks; a busy test relay; a test circuit extending from the calling plug to the test relay and controlling the relay; an auxiliary test circuit extending from the relay to the operator's telephone and controlled by the relay; and contacts on said relay adapted to remove the busy test conditions from the answering plug and jack when a busy test condition is encountered upon a tested line by the calling plug, substantially as described.

3. In a telephone system, a connective plug pair having two switching plugs and adapted to connect with the same line at the same time with both its switching plugs; a battery; and a ringing key forming a part of said connective plug pair and adapted to disconnect the battery from the calling line at one of its plugs and to connect a ringing generator to the line at the other of its switching plugs substantially as described.

4. In a telephone system, a call-answering plug, a ringing plug and a ringing key having contacts opening the talking conductors between the call-answering plug and its associated plug-pair apparatus while ringing upon the ringing plug.

5. In a telephone system, a test relay; a main test circuit through said relay and an auxiliary test circuit from said relay to the

operator's telephone equipment, said relay being adapted to connect together said main and auxiliary test circuits; a test circuit extending to the answering plug and a contact in said relay interrupting said circuit and removing the test potential from the answering plug when said test relay is operated.

6. In a telephone system a plurality of pairs of connecting plugs; a test circuit extending when completed through the body of one plug and the tip of another; and a test relay in each pair associated with the body of the answering plug and the tip of the calling plug and operating to remove all test potential from the answering plug body when a test current is received from the calling plug tip.

7. In a telephone system a plurality of pairs of connecting plugs; a test circuit extending when completed through the body of one plug and the tip of another; and a test relay in each pair associated with the body of the answering plug and the tip of the calling plug and operating to remove all test potential from the answering plug body when a test current is received from the calling plug tip and a contact upon said test relay and connecting the operator's telephone to the tip of the calling plug after the removal of the test potential from the body of the answering plug.

8. In a telephone system, a testing plug and a relay completing a circuit between said testing plug and the operator's telephone; and a contact on said relay breaking the test conductor of the answering plug prior to completing the connection from the operator's telephone to the testing plug.

9. In a telephone system, a telephone line; a connective device connecting with both limbs of said telephone line at each of two pairs of points, and means breaking the connections to the said line at both pairs of points when ringing at one of said pairs of points.

10. In a telephone system a plug pair comprising with other apparatus a ringing key cutting the talking conductors of both answering and calling plugs from all plug-pair apparatus when ringing upon the calling plug.

11. In a telephone system a plug pair connecting a source of constant current with its two plugs; a generator of ringing currents; and means for disconnecting both plugs from said source and connecting one plug with said generator of ringing currents.
